UNITED STATES PATENT OFFICE.

FRANK WANKEL, OF NEW YORK, N. Y.

KEY-CUTTING MACHINE.

1,225,539.

Specification of Letters Patent.

Patented May 8, 1917.

Application filed December 7, 1916. Serial No. 135,541.

To all whom it may concern:

Be it known that I, FRANK WANKEL, a citizen of the United States, and a resident of the city of New York, Ridgewood, borough of Queens, in the county of Queens and State of New York, have invented a new and Improved Key-Cutting Machine, of which the following is a full, clear, and exact description.

10 This invention relates to metal-working machinery and has particular reference to machines for cutting duplicate keys.

Among the objects of the invention is to provide a simple yet efficient and reliable 15 machine for the cutting of lock keys of the type commonly known as Yale, Corbin or similar keys in which notches, grooves or slots of varied lengths or widths are provided.

20 Another object of the invention is to improve the general construction of the machine, with respect to adjustment of the relatively movable parts providing for an 25 operation of the machine that is materially simplified and improved as to accuracy.

With the foregoing and other objects in view the invention consists in the arrangement and combination of parts hereinafter described and claimed, and while the invention is not restricted to the exact details 30 of construction disclosed or suggested herein except as defined by the appended claims, still for the purpose of illustrating a practical embodiment thereof reference is had 35 to the accompanying drawings, in which like reference characters designate the same parts in the several views, and in which—

Figure 1 is a vertical longitudinal section on the broken line 1—1 of Fig. 3;

40 Fig. 2 is a rear elevation;

Fig. 3 is a plan view;

Fig. 4 is a vertical sectional detail on the line 4—4 of Fig. 3; and

45 Fig. 5 is a detail perspective view of the guide post.

Referring now more particularly to the drawings, I show a machine comprising a rigid frame 10 having a base 11 designed to be secured or clamped in place by any 50 suitable means as, for example, an anchor bolt 12. The main portion of the frame constitutes what may be termed a table 13 formed along its side edges with grooves 14, constituting guideways. The table 13 55 also supports or carries a pair of vertically

projecting spaced standards 16, between which is positioned a novel form of rotary cutter 17 secured to a shaft 18 journaled in the standards and adapted to be driven by any suitable means including a wheel 19. 60

The cutter 17 is of disk-shape and provided on its periphery with cutting teeth 17^a and on at least one side with cutting teeth 17^b. The cutter wheel is provided also with a hub 20 which is of a length corresponding to the space between the standards 16, whereby endwise movement of the cutter along the axis of its supporting shaft is prevented.

I provide a carriage comprising a pair 70 of parallel side bars 21 and 22, which operate along the side edges of the table 13 and have ribs or tongues 23 projecting toward each other and operating in the guideways 14 of the table. These side bars are connected by transverse tie rods 25 having heads 26 adjacent to the bar 21 and having their opposite ends in threaded engagement with tapped holes in the opposite side bar 22. By rotation of these tie rods, the space be- 80

tween the side bars 21 and 22 is regulated, providing for a proper fit between the side bars and the table. In other words, the side bars are so adjusted that they will have sufficient looseness to slip readily lengthwise 85 of the table along the grooves 14, but not sufficiently loose to have any appreciable lateral play. After the tie rods are adjusted in this manner, they are preferably locked from rotation by means of set screws 26 90 tapped into the side bar 21. It will thus be seen that the carriage is adapted to slide freely longitudinally of the machine, such movement being limited in one direction by the end bar 25 impinging against the standards 16. The carriage also includes a transverse guide bar 27 fitted for endwise movement in a pair of aligned holes formed in the front ends of the bars 21 and 22, the axis of this guide bar being parallel to the 95

tie rods 25 and perpendicular to the direction of longitudinal movement of the carriage. The bar 27 is materially longer than the outside dimensions of the carriage so as to provide a considerable amount of 100 endwise movement, such movement, however, to be limited by any suitable means such as collars 28 secured to the ends of the bar.

The cutter 17, as will be observed from 110

the foregoing description, is mounted for rotation in a fixed plane perpendicular to the main plane of the table 13. 29 indicates a guide post secured rigidly to the front portion of the table 13 and having an active edge 29^a and an active side 29^b, forming a right angle corner having definite relation as to distance from the intersection of the cutter surfaces 17^a and 17^b and lying in the same vertical plane thereof. This post is locked in position by a set screw 30, whereby it may be adjusted vertically if desired, but for practical purposes it is held in fixed position.

31 indicates a clamping block or head having two fixed jaws 31^a and 31^b, having their axes parallel to each other and arranged at an oblique angle of approximately 45 degrees to the plane of the cutter. Co-20 operating with these fixed jaws are movable clamping jaws 32^a and 32^b for holding a master key or pattern M and a blank D to be made into a duplicate of the master key by the operation of this machine. The movable jaws are manipulated by winged nuts or their equivalent 33, which coöperate with threaded bolts 34 fixed in the head 31. Each fixed jaw of the head is rabbeted at 35 to receive the shank of the key to be secured thereto, whereby the back of the shank of each key is held in definite position, with respect to the other key. Each movable jaw, also, is provided with a downwardly projecting lip 36 projecting into the rabbet 35 and against the top of the key or blank. The cutting edge of the master key, like the corresponding edge of the blank to be cut, extends over or beyond the face of the head or fixed jaw toward the cutter. A plunger 40 by virtue of a spring 41 acts upwardly upon each movable jaw. The plunger is parallel to the threaded bolt 34 and serves also to prevent twisting movement of the movable jaw.

45 The head 31 is provided at its under surface with transverse parallel grooves 37 and 38, receiving respectively the guide bar 27 and the intermediate tie rod 25. The groove 37 is preferably deeper than the other, whereby the guide bar is received far enough within it to be gripped in fixed position by means of a set screw 39, or its equivalent, tapped through the front end of the head. The intermediate tie rod 25 co-50 operating with the other groove 38 serves, however, only as a guide or support for the head as it is moved laterally with the guide bar, with respect to the carriage. It will thus be seen that so far as permitted by the 55 guide post 29, the head is adapted to be moved laterally in either direction independently of the carriage, and longitudinally with the carriage, with respect to the table 13, and the parts secured thereon. In 60 other words, with the head moved to the

right, as viewed looking toward the cutter from the right side of Fig. 3, the master key being gripped in place and the blank to be cut being gripped in its place in a position symmetrically arranged, with respect to the master key, and with the cutter then rotated by any suitable means, the operator will move the head toward the cutter into contact with the guide post 29, beginning preferably at the hilt of the key. The active 75 guide corner or intersection of the faces 29^a and 29^b of the guide post will in effect follow the outline of the cut portion of the master key. Inasmuch as the head is rigid and the blank D bears the same relation to 80 the cutter as the master key does to the guide post, it follows that the blank will be quickly cut and with absolute precision as a duplicate of the master key. During this cutting action, the head is adapted for practically universal movement, with respect to 85 its plane or the plane of the keys.

The form of the cutter having its periphery of cylindrical form and its side of flat form is peculiarly adapted for the cutting 90 of the type of keys indicated, since the notches are commonly cut in the form of right angles or with their sides at right angles to each other corresponding to the intersecting faces of the cutter. However, 95 the active guiding edge of the guide post will follow a rounded notch as well as a square notch and the effect upon the blank will be the same in all cases. It is to be noted also that this machine is adapted for 100 the cutting of other types of keys than those illustrated with very little, if any, rearrangement or modification. This machine is simple in construction, easy of manipulation and absolutely true and reliable in 105 practical operation.

I claim:

1. In a key cutting machine, the combination of a stationary table having a pair of guide grooves along its opposite edges, a carriage movable longitudinally of the table and comprising a pair of side rails having tongues projecting into and glidable along said grooves, said carriage also comprising a pair of tie rods extending from one side 110 bar to the other and serving to determine the adjustment of the same with respect to the table grooves, said carriage having at one end a pair of aligned holes, a guide bar fitted in said holes and movable longitudinally of its axis therein transversely of the carriage and table, a clamping head for master and blank keys secured to said guide bar and slidable along one of the tie rods 115 for lateral movement with respect to the carriage and movable with the carriage longitudinally of the table, a rotary cutter journaled upon the table for action upon the blank, and a guide post fixed to the table in the plane of the cutter for coöperation with 120

125 130

the master key for determining the direction and extent of movement of the head and carriage.

2. The combination with a fixed table and 5 a rotary cutter journaled therein for operation in a definite plane, of a guide post secured to the table and having its operative portion in the plane aforesaid, a carriage comprising a pair of parallel side bars fitted 10 to the side edges of the table and adapted to reciprocate freely therealong, said carriage also including a pair of tie rods, each having a head at one end coöperating with one side bar and having its other end threaded in the other side bar, whereby the distance 15

between the side bars is accurately determined and means to lock the tie rods in adjusted position, a clamping head, means to secure master and blank keys to said head in parallel relation to each other for co- 20 operation with the side post and cutter respectively, and means to support said head upon the carriage for movement laterally independently thereof and longitudinally with the carriage whereby convolutions will be 25 formed by the cutter in the blank key exactly similar to the convolutions in the master key.

FRANK WANKEL.
